BACKWATER FLOOR DRAIN

Filed Dec. 29, 1928

INVENTOR.
EDWARD W. N. BOOSEY

BY

Frank E. Neary

ATTORNEY.

UNITED STATES PATENT OFFICE.

EDWARD W. N. BOOSEY, OF DETROIT, MICHIGAN.

BACKWATER FLOOR DRAIN.

Application filed December 29, 1928. Serial No. 329,234.

This invention relates to back water floor drains and its object is to provide a simplified construction of the drain head and support for the valve preventing back flow of water through the drain head, a feature of the invention residing principally in the provision of a separate casting of a character providing a depending chamber of two compartments open to the inlet of the drain head and a swing check valve for the outlet from the said chamber located above the drain head outlet all of which is hereinafter more specifically described and claimed.

The preferred embodiment of a drain head embodying my invention is shown in the accompanying drawings in which—

Fig. 1 is a vertical section of my improved drain head.

Fig. 2 is a perspective view of the insertible member or shell carrying the swing check valve.

In its preferred embodiment, the invention consists of the drain head 1 which may be of any desired form in cross section and having a shoulder 2 provided adjacent its upper end and a vertical peripheral flange 3. This drain head has an outlet hub 4 at its bottom offset relative to which a drain pipe 5 may be secured or caulked as indicated in Fig. 1. The drain head is arranged to receive the insertible casting 6 which is shaped on one side to provide a depending chamber 7 open at its upper end to the inlet which is covered by the usual grating 8. This grating it is to be noted, may rest directly upon a flange 9 with which the member 6 is provided at its upper end and seating on the flange 2 of the drain head.

If desired, a packing element 10 may be introduced between the flange 9 and the shoulder 2. This casting 6 has a sloping wall 11 extending from the flange on one side to and terminating with the depending vertical wall 12 of the member 6 which forms one wall of the chamber 7. The sloping wall 11 tends to direct material flowing into the head through the grating into the chamber 7 and these walls 11 and 12 and adjacent portion of the head form the outlines of a chamber 13 in the drain head directly over and open to the outlet conduit 5. The vertical wall 12 of the insertible casting 6 is apertured and threaded to receive a tubular member 14 having an angular finished face at its discharge end to receive the valve 15. This valve is supported on a lever 16 pivoted at 17 to the upper

side of the member 14. While this valve lies in a plane at an angle to the vertical it still at its lower end does not extend beyond the vertical line passing through the axis of the pivot 17 and thus normally closes by gravity. While the valve opens freely to flow of fluid the drain head and chamber 7 it will instantly close under back flow through the conduit 5 and chamber 13.

The sloping wall or floor 11 is provided with a circular threaded flange 18 to receive a removable plug 19 permitting access to the chamber 13 without necessity of removal of the casting 6 and thus any material tending to clog in the chamber 13 or outlet pipe 5 is easily removed through the aperture closed by the plug 11. This aperture also permits access to the valve and cleaning of the seat therefor or removal of the valve and member 14 if repair is necessary.

By providing this insertible shell or member 6 this drain head may be used with or without a back water swing check valve in conjunction therewith and thus in manufacturing the drain head 1 may be made of standard form and where an installation is to be made requiring a back water check valve this shell 6 may be inserted. Thus, the amount of stock necessary to be carried by the manufacturer may be reduced and by standardizing the construction it may be sold on the market at a lower price.

Having thus briefly described my invention, what I claim is—

1. A back water floor drain comprising a hollow head having an inlet at one end and an outlet at the opposite end, said inlet end being formed with a shoulder and peripheral vertical flange, a cast shell having a peripheral flange adapted to seat on the shoulder of the said head, one portion of the shell being shaped to provide a depending chamber open at its top within the flange, said chamber having a vertical wall and a sloping wall extending from near the top of the shell and downwardly inclined terminating at the vertical wall, said shell when inserted providing a chamber in the drain head practically directly over the outlet to the head, said depending portion of the shell having an outlet in the vertical wall near its bottom and a swing check valve supported exteriorly of the said depending chamber tending to close by flow backward through the outlet of the drain head.

2. A back water floor drain comprising a

hollow head having an inlet end adapted to be positioned substantially flush with the floor surface, and an outlet of smaller diameter at its opposite end, the said inlet end being provided with a shoulder and a vertical peripheral flange thereabout, a grating for positioning therein, a shell detachably supported on the said shoulder beneath the grating formed to provide a depending chamber on one side of approximately half the cubicle content of the head and having a vertical wall at about its center plane terminating at its upper end below the upper open end of the shell, a wall or floor upwardly inclined from the vertical wall to the peripheral portion of the shell providing for drainage of material into the said depending chamber of the shell, a discharge opening for the said chamber at about the bottom of the vertical wall, a swing check valve therefor opening by reason of flow entering the depending chamber and closing by reason of back flow through the outlet of the head.

3. A back water floor drain comprising a hollow head having an inlet end adapted to be positioned substantially flush with the floor surface and an outlet at the opposite end of smaller diameter, a detachable shell adapted for insertion in the head supported therein intermediate the inlet and outlet ends, said shell being formed to provide a depending chamber on one side, said chamber having a vertical wall occupying approximately the center plane of the shell and terminating below the upper end thereof, a downwardly inclined wall or floor extending from the side of the shell opposite the chamber and terminating at the said vertical wall, an aperture in the said inclined wall permitting access to the interior of the head at one side of the depending chamber, the said vertical wall having an opening near its lower end, a tubular member insertable therein providing an outlet, a swing check valve carried on the end of the said

tubular member, the said valve being accessible through the said opening of the inclined floor and positioned approximately directly over the outlet for the head, and a removable grating at the inlet end of the head and covering the shell.

4. A back water floor drain comprising a hollow head having an inlet at one end and an outlet at the opposite end of smaller diameter and the axis of which is offset and parallel to the axis of the inlet, a shell insertable in the inlet and detachably secured to the head, said shell being formed with a depending chamber at one side of the outlet for the head, said shell having a vertical wall at about its center plane and an inclined wall extending from the top of the vertical wall to the side of the shell over the outlet, said inclined wall having a closable opening, and a swing check valve on the outer side of the said vertical wall directly over the outlet for the head providing a closure for the outlet opening provided for the depending chamber of the shell.

5. A back water floor drain comprising a hollow head having an inlet at one end and an outlet at the opposite end, a metal shell detachably secured therein in sealed relation thereto and into which fluid passes from the inlet of the head, said shell having a depending hollow portion on one side and an inclined wall extending from the hollow portion to the opposite side and, when assembled with the head, providing a chamber within the head beneath the inclined wall open directly to the outlet of the head, a check valve supported in the depending portion of the shell tending to open by a flow of fluid into the shell and to close by back pressure in the chamber open to the outlet.

In testimony whereof I sign this specification.

EDWARD W. N. BOOSEY.
